(57) **CLAIM**

The ornamental design for an automobile as shown and described.

DESCRIPTION

1. Automobile
2. Automobile
- 1.1 : Front
- 1.2 : Back
- 1.3 : Top
- 1.4 : Cross sectional
- 1.5 : Right
- 1.6 : Left
- 2.1 : Front
- 2.2 : Front
- 2.3 : Front
- 2.4 : Front
- 2.5 : Cross sectional
- 2.6 : Top
- 2.7 : Back
- 2.8 : Right
- 2.9 : Left

The broken lines in the figures form no part of the claimed design; the dash-dotted lines in the figures represent the unclaimed boundaries; the part for which protection is sought is the rectangular areas surrounded by a solid line in one side and dash-dotted lines in the other three sides; the outside of such rectangular areas forms no part of the claimed designs; the oblique line shadings shown in the figures represent transparency or translucency; for the designs bottom views are omitted because the bottom sur-

(Continued)

face of the article is not visible during use; figs. 1.4 and 2.5 are horizontal cross-sectional views of the claimed area; figs. 2.2-2.4 are front views with changing status of the light control sheet; the monochrome tone on the light control sheet showing changing status among figs. 2.2-2.4 represents changes in brightness and transmittance; lighter tone represents higher brightness and transmittance and darker tone represents lower brightness and transmittance.

1 Claim, 15 Drawing Sheets
